UNITED STATES PATENT OFFICE.

CALEB T. WOODBUY, OF NEWBURYPORT, MASSACHUSETTS.

DESIGN FOR A PAPER-WEIGHT.

SPECIFICATION forming part of Design No. 15,123, dated July 1, 1884.

Application filed April 28, 1884. Term of patent 3½ years.

To all whom it may concern:

Be it known that I, CALEB T. WOODBUY, a citizen of the United States, residing at Newburyport, in the county of Essex and State of Massachusetts, have invented and produced a new and original Design for a Paper-Weight, of which the following is a specification, reference being had to the accompanying drawings, forming a part thereof.

10 Figure 1 is a top view of my newly-designed paper-weight, and Fig. 2 a section thereof on the line $x x$.

The paper-weight containing my design represents stone-work S, some of the blocks thereof in being laid to constitute buttresses A. A' B. B' and an intermediate arch, C.

The leading features of my design are the body S, the two buttresses B B', and the arch C.

I claim—

The design for a paper-weight shown and described, the same consisting of the body S, buttresses, and arch.

In testimony whereof I have signed my name to this specification in the presence of two subscribing witnesses.

CALEB T. WOODBUY.
